HENRY A. GARTNER, OF BROOKLYN, NEW YORK, ASSIGNOR OF ONE-HALF TO ROBERT J. CAMPBELL, JR., OF DREXEL HILL, PENNSYLVANIA

COMBINED HEEL AND ARCH SUPPORT FOR FOOTWEAR

Application filed August 17, 1927. Serial No. 213,451.

This invention relates to footwear embodying means affording support at the instep for the wearer's feet, whereby falling or lowering of the arches is scientifically prevented. More

5 specifically my present improvements contemplate a combined heel and arch support, preferably of resilient material, that is durable and highly efficient for the purposes had in view.

10 An object of my invention is to provide a combined heel and arch support which correctly sustains the longitudinal and transverse arches of the wearer's foot—at all times—from the ground upwardly, while at the same 15 time properly cushioning the heel.

Another object is the provision of novel means, that will scientifically support the wearer's foot under all normal conditions, while according free natural movement for 20 the several foot bones; that preserves the original curvature of footwear shanks relative to the sole portion thereof; and which prevents formation of concavities or other irregularities in the inner sole portion that 25 due to the development of weak, delicate, and flat feet.

Other objects and advantages will be manifest from the following detailed explanation of my invention, which, when considered in 30 connection with the accompanying drawings illustrates a practical embodiment thereof; while the appended claims define those features alleged as novel and patentable.

In the drawings:—

35 Fig. I is an underside plan view of a shoe for masculine wear embodying one form of my invention.

Fig. II is a side view of the same, with a portion of the upper removed for convenience 40 in illustration.

Fig. III is a transverse section, taken as indicated by the arrows III—III in Fig. I; and,

Fig. IV is a similar sectional view on the 45 plane designated by the arrows IV—IV in Fig. I.

Referring more particularly to Figs. I—IV of the drawings, a conventional shoe is comprehensively designated by the numeral 6, the 50 same comprising an upper 7, and sole 8; to

which my novel combined heel and arch supporting device, generally denominated 9, is applied and secured, as hereinafter fully set forth.

This combined device 9, is preferably made 55 of suitable resilient material such as rubber, leather, or any other appropriate composition useful in the art; and, it embodies—in a unitary structure—the heel 10 with a forwardly directed arch supporting portion 11, 60 effective to scientifically sustain the longitudinal and transverse arches of the wearer's foot. The supporting portion 11, it is to be particularly remarked, extends, when applied to the shoe sole 8, by virtue of its novel unconstrained configuration inside of the middle 65 of the heel 10, forwardly under the inner aspect of the wearer's foot, with its bearing surface 12 offset sufficiently from the longitudinal center line of the shoe 6, to correctly 70 sustain the articulation of the astragalus and scaphoid bones; as well as the metatarsal-phalanx articulation of all the toes substantially flush with the heel 10 and ball 13 of the shoe, even when off the ground. Particular attention is directed to the fact that 75 the supporting portion 11, of the device 9, is of somewhat fish-tail outline in plan, and that it normally—or before attachment to the shoe 6—extends co-planar with the top of the 80 heel 10. In other words, the ground engaging surface thereof gradually tapers somewhat arcuately upwards from the point of emergence 14 with the heel tread to the relatively wider knife-edge 15, where it joins the 85 shoe sole 8 transversely in the region of the ball 13. Furthermore, the fish-tail portion is slightly tapered transversely from a high point 16 adjacent the inner border edge of the shoe sole 8, gradually down to a low point 90 17 merging into the outer border edge of said sole, whereby the weight of the body is firmly sustained from the inner to the outer side of the foot without any strain upon the transverse arch.

The supporting portion 11, it is also to be noted, aligns snugly with the inner border edge of the shoe shank 18, whereat it is conveniently molded as indicated by the line shading 19—Fig. I. On the other hand, the 100

outer side 20 of the portion 11 is spaced relative to the outer border edge 21, of the shank 18; or, more specifically—and as best appreciated from Fig. I—the side 20 gradually 5 sweeps inwardly from the heel 10 to the bend 22 of the fish tail, where it flares sharply outward to the knife-edge 15, above referred to.

In some instances—such as when it is desired to provide the shoe 6 with a rubber sole 8—the device 9 may be built up of laminae 10 and integrally united to the sole 8 by vulcanizing; or, when of leather, the several “lifts” may be secured together by brads in 15 the known manner.

From the foregoing it will be understood that the provision of the heel 10 with an integral arch supporting portion 11, co-extensive with the shoe shank inner border edge 20 to the region of the sole ball 13, with said portion on an angular turn and following the transverse pedis muscle, that it will sustain the entire longitudinal and transverse arches. In other words, I provide a correct 25 support for the metatarsal-phalanx articulations from the fifth or little toe, to that of the big toe. Also, it is noteworthy that the support 11 graduates from substantially nothing at the outer side or edge of the shoe sole 30 8, to an elevation of about one-eighth of an inch—for example—on the inner edge thereof, in the region of the ball 13; and similarly the portion 11 gradually increases in thickness from its frontal knife edge rear- 35 wards till merging into the heel tread.

From the preceding description, it is thought my invention will be well understood; while the right is hereby reserved to make such variations in shape, as are necessary to adapt the same to differing styles of 40 footwear, without departing from the generic aspect of said invention, the scope whereof is encompassed by the subjoined claims.

Having thus described my invention, what 45 I claim is:—

1. As an article of manufacture a support embodying a heel portion with a forwardly-directed section adapted to correctly sustain the longitudinal and transverse arches of 50 the human foot, said section before application to a shoe extending co-planar with the top of the heel but—when applied thereto—being flexed downward from a point inside of the middle of the heel forward under the 55 inner region of the ball, with its bearing surface extending sufficiently from each side of the longitudinal center to repose under and support the articulation of the astragalus and scaphoid bones, as well as the metatarsal 60 phalanx articulations of all the toes.

2. As an article of manufacture a support 65 for footwear embodying a heel with a forwardly-extending fish-tail section initially having its upper surface co-planar with the top of the heel and its ground engaging face

tapering arcuately upward from the heel tread, but designed when downwardly flexed to correctly support the longitudinal and transverse arches of the wearer's foot, said fish-tail section merging into the ball of the 70 foot wear and being transversely graduated in thickness from a high point adjacent the inner marginal edge to a low point adjoining the outer marginal edge of the foot wear sole.

3. As an article of manufacture a support 75 for foot-wear embodying a heel with a forwardly directed prolongation initially having its upper surface co-planar with the top of said heel but when downwardly flexed conforming to the shank of the foot wear to 80 which it is applied, said prolongation comprising a body portion of substantially even thickness designed to sustain the inner part of the foot arch, and a fish-tail spread tapered down longitudinally as well as transversely 85 outwards to merge into the footwear sole at that region known as the ball, so as to correctly sustain the metatarsal phalanx articulation of the foot with capacity for 90 natural movement at all times.

4. As a new article of manufacture a combined heel and arch support for shoes, the arch support being of fish-tail outline having its upper surface initially co-planar with the top of the heel and the fin portion adapted 95 when downwardly flexed to merge into a shoe sole at that region known as the ball, said fin portion conforming along its inner edge to that of the shoe shank with its outer edge spaced relative to the outer border edge of 100 said shank with an inward sweep intermediate the heel portion and fish-tail bend, said arch supporting portion tapering downwardly outwards from a high point on the inner side thereof so as to correctly sustain the metatarsal phalanx articulations at all times.

5. As a new article of manufacture an arch support for foot wear embodying a heel and integral shank designed to sustain the inner part of the foot arch—from the heel forwardly, with an integral terminal widened portion having outwardly-downward taper in the region of the foot known anatomically as the ball, for the purpose specified.

In testimony whereof, I have hereunto 115 signed my name at Penn Yan, New York, this ninth day of August, 1927.

HENRY A. GARTNER.
